UNITED STATES PATENT OFFICE.

GEORGE H. BARBOUR, OF PITTSBURGH, PENNSYLVANIA.

RAILWAY-TRACK STRUCTURE AND METHOD OF MAKING SAME.

1,252,647.

Specification of Letters Patent.

Patented Jan. 8, 1918.

Application filed May 31, 1916. Serial No. 100,762.

To all whom it may concern:

Be it known that I, GEORGE H. BARBOUR, a citizen of the United States, residing at Pittsburgh, Allegheny county, Pennsylvania, have invented a new and useful Improvement in Railway-Track Structures and Methods of Making Same, of which the following is a full, clear, and exact description, reference being had to the accompanying drawings, forming part of this specification, in which—

Figure 1 is a cross sectional view of a railway rail joint embodying my invention.

Fig. 2 is a side view of the same.

15 Figs. 3, 4, 5 and 6 are transverse vertical sections showing my invention applied, respectively, to four other forms of track structures.

Fig. 6^a is a section on the line VI—VI of Fig. 6.

Fig. 7 is a detail sectional view showing the initial shape of one form of rivet.

Fig. 8 is a similar view showing the completed rivet.

25 Figs. 9 and 10 are views similar, respectively, to Figs. 7 and 8, but showing another form of rivet.

Figs. 11 and 12 are diagrammatic views showing different cross sectional forms of 30 ties which may be employed.

Fig. 13 is a sectional plan view, partly diagrammatic, illustrating successive steps in the formation of the tubular rivets, and

35 Fig. 14 is a sectional plan view illustrating one method of removing a rivet.

My invention has relation to railway track structures, and is designed to provide a structure of this character in which the parts of the structure are secured in a novel and 40 effective manner, the use of ordinary track bolts being obviated and such bolts being replaced by rivets of a peculiar character. My invention also provides a novel method for the manufacture of such structures.

45 My invention is particularly applicable to rail joints, although it may be used to advantage in various other structures, such as compound rails, rail braces, rail fastenings, etc.

50 Some of the main objects and advantages of my invention will be hereinafter pointed out more in detail.

Referring first to that embodiment of my invention shown in Figs. 1 and 2, the numeral 2 designates a track rail, 3 the splice bars, 4 is a metallic rail tie, and 5 suitable

fastenings attached to the tie and engaging the base of the rail.

In accordance with my invention these parts are secured together by means of a plurality of hollow tubular rivets 6. These rivets are each initially of the form shown in Fig. 7. After the joint parts have been assembled and these rivets placed in position, they are completed and secured in the manner shown in Fig. 13. This figure represents three successive operations. In the first operation the clamping jaws 7 of a riveting bull are set against one of the fish plates or splice bars 3, and a punch die 8 is operated at the other side of the structure, the punch point 8^a entering into the headed end of the hollow rivet and expanding the same within the rivet hole 10 in the splice bar. This rivet hole is preferably either punched in tapered form as shown, or is punched straight and tapered or countersunk to conical form. After this end of the rivet has been expanded to fill this tapered or conical hole as shown at 6^a in Fig. 13, a similar punch die 9 is engaged with the opposite end portion of the rivet, and this end portion is similarly expanded and is at the same time rolled or peened over to form a head 6^b. This produces a finished tubular rivet having a central straight portion 6^c extending through the web of the rail, and an expanded conical portion 6^a filling the tapered openings in the splice bars 3. Where it is desired to form an insulated joint, insulating sleeves or bushings may be used around the rivet, as shown at 10 in Fig. 1, and insulating strips 11 may also be placed between the bearing surfaces of the splice bars and rails.

95 It will be noted by reference to Fig. 1 that the splice bars are of peculiar form, in that each bar has four flanges, viz., two short flanges 3^a which fit the fishing angles of the rail, and two deep outer flanges 3^b which extend a considerable distance from the rail head and preferably terminate in vertically directed enlargements or ribs 3^c. These splice bars are of substantially symmetrical cross section about their horizontal axes and are of a strength approximating that of the rail.

100 The present tendency toward increase in rail heights is largely the result of an attempt to obtain a greater fishing distance 110 between the head and base flanges. This increase in height, which results in an increase

in stiffness, is detrimental, since the stiffer the rail the less able it is to adjust itself to the inequalities of the road bed. That is to say, the stiffer the rail, the less able is it to undergo the necessary "weaving" movements which it must have owing to the cushioning and yielding action of the ballast. The ordinary rail is also weak sidewise. That is to say, it is too high for its width, or is too narrow for its height. My invention enables the use of a relatively low stocky rail section of a width substantially equal to its height and which, though weaker vertically than rails of standard design, is much better adapted to withstand extraordinary shocks and blows and to adjust itself to the inequalities of its road bed, due to its greater transverse strength and increased flexibility. This reduced height is made permissible by reason of the form of angle bars illustrated and the use of the tubular rivets, the heads of which can be seated within relatively narrow channels between the flanges of the splice bars where the usual nuts could not be employed. By the use of the tubular rivets the rivet heads may be formed in the manner described. This could not be done with ordinary solid rivets, without upsetting their body portions in the open spaces between the rails and the splice bars. By using tubular rivets expanded in the manner described, this difficulty is overcome, and the rivets used are of greater strength than would be possessed by bolts of the same diameters. By the use of power means such as a compression riveter, the splice bars may be driven home at any desired pressure and riveted there; and by a similar operation may be again compressed and the rivets tightened should the joint work loose, thereby greatly facilitating the maintenance of tight joints and greatly reducing the liability of breaks in the webs of the rails. Such breaks usually occur at the bolt holes, either as longitudinal splits or as a breaking out of pieces of the rail due to the leverage set up at a loose joint and the severe blows to which the rail is there subjected. The use of power operated riveters enables a small crew of experienced workmen to attend to the upkeep of long stretches of track, and thus eliminates a large percentage of the unskilled and unreliable floating labor now commonly employed for track maintenance.

When it is necessary to remove a joint, this can be effected by the use of a power operated punch 12 with suitable clamps 13 at the opposite side of the rail, pressure being applied to the punch in the manner indicated in Fig. 14 to shear the rivet head at that end.

It will be noted that the lower deep flanges 3^c of the splice bars terminate above the surface of the tie, so that the joints do

not interfere with any desired spacing of the ties. These overhanging flanges also clear the rail fastenings, so that no notching or cutting of such flanges is necessary. With wooden ties the ordinary spike fastenings may be employed. With metal ties, fastenings such as shown at 5 may be riveted to the ties and engage the base flanges of the rail in the manner shown in Fig. 1. I also preferably chamfer the lower corners of the base flanges as indicated at 14. This increases the strength of the rail section under the conditions of combined vertical, lateral, and torsional strains, due to the reduction in the distance from the center of gravity of the rail to the extreme lower corners of its base.

My invention is also well adapted to the use of metal ties of different forms. In Figs. 1 and 2 I have shown a tie formed of rolled sections, consisting each of the intermediate straight web portion 15, the upwardly bent portions 16, one at each side of the web portion 15, each of said upwardly bent portions carrying the L-shaped flange 17 forming a bearing for the rail base and also a bearing portion to which the fastenings 5 are riveted. The edge portions 17 of each tie beyond the outwardly bent portions preferably extend horizontally in the horizontal plane of the web 15. This form of tie not only gives a double seat and fastening for the rails, but a largely increased bearing on the ballast, so that fewer of these ties are necessary for a given length of track. These ties also permit of proper tamping of the ballast.

Fig. 11 shows another form of sheet metal tie which is bent or arched upwardly at its center portion as indicated at 18 with the two projecting L-shaped rail supporting flanges 19 and the horizontal edge flanges 20.

Fig. 12 shows another form of tie similar to that shown in Fig. 2, except that the horizontal web portion 15 is omitted and the edge flanges 17^a extend in a vertical instead of a horizontal direction.

While I prefer to employ rivets which are tubular throughout their length, I may employ rivets having an ordinary head 21 at one end, and having the other end portion tubular and expanded and headed in the manner above described. This form of rivet is illustrated in Figs. 4, 9 and 10.

In Fig. 3 I have shown my invention applied to a track structure in the form of a compound rail wherein the numerals 22 designate two separated supporting members having head portions 22^a having the undercut projections 23 between which is clamped a dovetailed projection 24 of a tread member 25. The two members 22 are secured by tubular rivets 26, similar to those first described. The rail supporting member 27, which may be either a tie or a tie plate, is

shown as having a T-shaped upward projection 28 which acts as a spacer for the members 22.

In Fig. 4 I have shown another form of compound rail in which the separable tread 29 is secured to the supporting member 30 by means of a brace 31 engaged at its upper end with the tread 29 and at its lower end caught between one edge of the base of the rail and a projection 32 on a tie plate 33. The brace and rail are secured to each other by means of rivets 34, which I have shown as being of the form illustrated in detail in Figs. 9 and 10.

Fig. 5 shows another compound rail structure in which the detachable tread 35 is secured to its supporting member 36 by a clamping member 37 secured to the web of the rail by tubular rivets 26^a. This figure also shows the use of similar tubular rivets 38 for securing the rail fastenings 39 to the tie 40.

Figs. 6 and 6^a illustrate the use of tubular rivets 41 for securing the rail brace 42 to the rail 43. This rail brace is held at its lower end between one edge of the rail and the projection 44 of the tie plate 45. The brace is preferably of the flanged form shown, its flanges 45 abutting against the web of the rail.

I do not limit the application of my invention to the particular track structures which I have herein shown and described, since obviously it may be embodied in various other types of such structures.

By the terms "hollow" and "tubular" as used herein and in the appended claims, I intend to cover a rivet which is hollow along its entire length, as shown, for instance, in Fig. 1, or which is hollow for a portion or portions of its length.

The rail tie herein shown and described will form the subject matter of a divisional application.

I claim:

1. A railway track structure, comprising a tread member, a plurality of engaging members, and a plurality of rivets holding said members in engagement, said rivets traversing an open space between the members and being hollow at the portions thereof which are seated in said engaging members, substantially as described. 45

2. A railway track structure, comprising a tread member, an engaging member, and a hollow rivet holding said members in engagement, said rivet traversing an open space between the members, substantially as described. 55

3. A railway track structure, comprising a tread member, members engaging the rail member and having tapered rivet holes therein, and rivets securing said members and having expanded conical portions filling said tapered holes, substantially as described. 60

4. A railway track structure, comprising a tread member and an engaging member, said members having portions in contact with each other and other portions which are separated by an intervening space, and a hollow rivet holding said members in engagement and traversing said space, substantially as described. 70

5. The herein described method of securing the parts of railway track structures, 75 which consists in inserting a tubular rivet through the engaged parts, compressing the parts, and while under such compression, expanding at least one end portion of the rivet and forming a head thereon, substantially as described. 80

In testimony whereof, I have hereunto set my hand.

GEORGE H. BARBOUR.
